UNITED STATES PATENT OFFICE.

HERBERT S. WOODWARD, OF CARBONDALE, PENNSYLVANIA.

PERFORATED INDENTED SCREEN.

Application filed February 27, 1924. Serial No. 695,391.

To all whom it may concern:

Be it known that I, HERBERT S. WOODWARD, a citizen of the United States, and a resident of the city of Carbondale, in the county of Lackawanna and State of Pennsylvania, have invented certain new and useful Improvements in Perforated Indented Screens, of which the following is a specification.

10 My invention relates to perforated indented screens for the screening of coal, ore and similar materials, and more particularly to the construction of the screen plates themselves, and the arrangement and disposition thereon of indented projections operative to impart strength and rigidity to the plate and to evenly distribute over the entire surface thereof the material being screened as it passes over or traverses the 20 length of the screen.

It will be understood that the indented perforated screen plates are adapted to be used as the bottom of a long inclined trough-like structure to which is imparted 25 a jogging or longitudinally reciprocating motion by any suitable mechanism (not shown). Coal, slate, ore or similar materials delivered to the high end of the screen is caused to gravitationally traverse the 30 length of the screen and such of the material as may be of a size to pass through the perforations of the screen will be separated out so that pieces of material delivered at 35 the lower end of the screen will be larger than the perforations in the screen.

As the mechanisms for imparting motion to shaking screens for assorting coal and similar materials to size are well known, it is deemed unnecessary to illustrate such 40 mechanism in order to understand my invention which, as above stated, relates to structure of the indented plates, a series of which forms the bottom of the screen. These perforated plates, in general, are rectangular in form; are of the full width of 45 the screen in which they are to be used; and a number of these plates are secured together substantially end to end to make a shaking screen of any desired length.

On each of the sheets of the drawings is illustrated one plate and a portion of the next adjacent plate of a screen.

The objects of my invention are to provide a perforated plate provided with indented projections thereon disposed prefer-

ably symmetrically with respect to the longitudinal axis of the plate, although in some instances the indented projections may be arranged symmetrically with respect to both the longitudinal axis and the transverse axis of the plate.

A further object of my invention is to provide such a shape and arrangement or disposition of the indented projections on a screen plate that they may be pressed into the sheet with a single die not substantially larger than half the area of the plate.

A further object of my invention is to provide a perforated screen plate with indentations which will not unduly retard the passage of the material over the screen and at the same time to provide a type or kind of indentation which will cause the loose material passing over the screen to be thoroughly agitated and travel a substantially zigzag path over a screen plate.

It is to be understood that screen plates are made of comparatively thin sheet metal to facilitate the punching therein of the perforations through which the material is to be screened, but in punching such plates with such perforations the sheet necessarily becomes more or less unevenly stretched and consequently warped so that the surface of a plate which is merely perforated is wavy or uneven, all of which is undesirable in these screens.

It is to be further understood that screen plates, made of thin flat sheet material, necessarily bend or flex downwardly toward the middle or longitudinal axis of the screen when a load or charge of loose material is passing thereover and that this bending of the screen plates at their longitudinal axis or median line tends to concentrate at the 90 middle of the screen the material traversing therethrough, thus preventing a thorough and complete screening of the material or the assorting of the material to a predetermined size.

It is the object of my invention to provide such a perforated plate with indentations or indented projections of such a nature and so disposed over the surface thereof such as will straighten the plate during the indenting process, take up the unevenly stretched material formed during the perforating or punching process, and render the plates flat, except for the projections indented therein, and strong and stiff.

A further object of my invention is to provide projections which will tend to tilt and agitate the pieces of coal, slate, etc., passing thereover, so that smaller pieces will 5 not ride on the larger pieces to be carried thereon and delivered together therewith out of the screen at the lower end thereof. The object of my invention is to provide the perforated plate with projections over 10 which the material will rock and topple to thoroughly agitate the material passing thereover, thereby giving the smaller pieces ample opportunity to fall through the perforations.

15 A further object of my invention is to so arrange the indentations of one row as to overlap those of an adjacent row creating a practically continuous indented surface which takes up the stretch produced in the 20 sheet by the perforating process to which it has been previously subjected.

25 A further object of my invention is to provide a perforated screen plate with indented projections in the form of low triangular pyramids, one base-line of each of which is parallel to the longitudinal axis of the plate and screen and with the two base-lines extending outwardly from the longitudinal axis of the plate, or inwardly toward 30 the longitudinal axis of the plate, depending upon whether the indentation is to be used to spread the material outwardly toward the edges of the screen in the one case, or to concentrate it toward the middle 35 of the screen in the other case.

40 A further object of my invention is to provide a screen plate of the character above described, with indentations in the form of triangular pyramids directing the material outwardly toward the sides of the screen during 45 its passage thereover and with the inclined ripples tending to concentrate or direct the material inwardly toward the middle of the plate, said ripples or ridges being successively of increasing height and preferably increasing width outwardly from the longitudinal axis of the plate.

50 A further object of my invention is to provide a perforated screen plate with rows of triangular projections operative to cause the material passing thereover to move outwardly toward the sides of the screen and to provide between said rows of projections ripples of successively increasing height and 55 width as the series of ripples approach the sides of the plate to offer increasing resistance or impedance to the lateral flow of material as it approaches the sides of the screen, and with series of parallel ripples between the side of the screen and the first 60 row of projections to concentrate the material passing thereover and to direct it toward the longitudinal axis of the screen.

65 Other objects of my invention will appear in the specification and claims below.

In the drawings forming a part of this specification and in which the same reference characters are employed throughout the various views to designate the same parts,

70 Fig. 1 is a plan view of a portion of a shaking screen trough showing one complete indented screen plate and a portion of a second like plate secured thereto as they would be secured together to form the perforated bottom of a shaking screen;

75 Fig. 2 is a transverse vertical section on the line 2—2 of Fig. 1;

80 Fig. 3 is an enlarged fragmentary plan view of the lower left hand corner of the plate shown in Fig. 1;

85 Fig. 4 is a view similar to Fig. 1 showing a modified form of perforated indented screen plate wherein concentrating ribs or ripples are dispensed with, and the material is given a zigzag motion over the surface of the plate by pyramidal indented projections only, said projections being disposed symmetrically on the plate with respect to both the longitudinal and transverse axes of the rectangular plate;

90 Fig. 5 is a vertical sectional view on the line 5—5 of Fig. 4;

95 Fig. 6 is a fragmentary enlarged view of the upper left hand corner of the plate shown in Fig. 4.

100 Referring to Figs. 1, 2 and 3, the sides 1—1 of a shaking screen are provided with a series of bottom plates 2—2, each rectangular in shape and having its side edges 3—3 secured to the sides 1—1 of the screen by bolts 4—4. The bottom plates 2 may be overlapped at their adjacent edges and secured together by rivets or bolts 5 or they may be arranged with abutting adjacent edges. The screen thus formed and comprising the sides 1—1 and a series of bottom plates 2, is mounted or positioned at a relatively slight incline, with the receiving end higher than the delivery end, and a back and forth reciprocatory movement is imparted thereto, as is indicated by the double-headed arrow 6.

105 Each plate 2 is symmetrical with respect to its longitudinal axis or the longitudinal median line 7—7 of the screen, as to the indentations or indented projections formed therein. It is to be noted that in referring to the plates shown in the drawings, I have considered the longitudinal axis of the plate to be the line midway between and parallel to the shorter sides of the plate, because that line is coincident with the longitudinal axis of a completed screen having its bottom composed of a plurality of plates 2. In other words, I have considered each plate 2, 110 to be shorter than it is wide.

115 The projections indented into the perforated screen consist of a plurality of inclined rows 8—8, 9—9, 10—10 of triangular pyramids 11 symmetrically disposed with re- 120

125

spect to a central row or series 12 of preferably quadrangular pyramidal projections 13-14 positioned with one diagonal of the base of each coincident with the longitudinal axis of the plate 2.

Between each adjacent row or series of pyramidal projections is provided one of a series of riffles or ridges 15-15, 16-16 and 17-17, one of each pair being on opposite sides of the longitudinal axis of the plate.

Between the outer rows 10-10 of projections and the side edges 3-3 of each plate are provided riffles 18-18, 19-19 and 20-20. These riffles are all preferably parallel on each side of the median line of the plate and converge as they approach the rear edge 21 of the plate so as to tend to concentrate or move the material passing thereover toward the central or longitudinal axis of the plate. The two innermost riffles 15-15 preferably meet adjacent the rear end or edge 21 of the plate, forming what may be termed a V-shaped riffle 15-15 embracing the central series or row 12 of projections 13-14.

The riffles 15, 16, 17, 18, 19 and 20 are, generally speaking, made of progressively increasing width and height from the middle or median line of the plate 2 outwardly toward the sides of the plate. Thus, the riffles 15 in the embodiment of my invention shown in Fig. 1 are preferably about one and one-half inches wide and one-quarter of an inch in height, and the riffles 20 are preferably two and one-half inches wide and five eighths of an inch in height. Between these two extremes the intermediate riffles increase gradually from the dimensions of the riffles 15 to the dimensions of the riffles 20.

The heights of the pyramidal projections 11, 13 and 14 are preferably alike and of the height of the riffles 15. These dimensions are merely given so that a fair idea of the proportions and relations of the various indented projections with each other may be immediately understood. The exact dimensions, of course, form no part of my invention inasmuch as they will vary depending upon the kind of material to be treated or screened and the size to which it is to be assorted or graded by the operation of the screen.

Substantially the entire surface of each screen plate 2 is covered with punched perforations 22 all of the same size. It is to be understood that these perforations 22 are preferably made in the plate before the pyramidal projections and riffles are impressed therein because, as above stated, the perforating or punching process tends to warp the plates by expanding or stretching the metal, and the impressing of the projections and riffles therein after the

punching process has been completed straightens the plates by taking up the expanded metal.

The front edge 23 of the plates 2 is preferably parallel with the rear edge 21 and both may be provided with a row of perforations 24 for rivets 5.

One base line of each of the pyramidal projections 11 is preferably disposed substantially parallel to the longitudinal median line 7-7 of the plate 2 and the other two base lines converge in a direction away from said line 7-7. One diagonal of the bases of the quadrangular pyramids 13 and 14 is preferably arranged coincident with the median line 7-7 of the plate 2.

I have shown by arrows 25 on the right hand half of the plate 2 the general direction of the pieces of coal forming the bottom of a layer of coal as it traverses that portion of the screen. The pieces near the center of the screen will tend to be crowded laterally by the inclined face of the pyramid 13 and toward the riffle 15. As the jogging of the screen continues and the material moves on, some of it will pass over the side walls of the pyramid 13 and pass down toward the pyramid 14 and will there be deflected toward the riffle 15. Part of the material will pass down the screen between the pyramid 14 and the riffle 9 and will be concentrated toward the middle of the screen at the rear edge thereof by the riffles 15.

The piling up of the material between the pyramid 13 and the riffle 15 will force some of the material over the riffle 15 and between the first two pyramids 11 of row 8 of projections 11. Other of the material will pass between the pyramid 13 and the riffle 15 and will accumulate in the space between the pyramid 14 and the riffle 15 where the above-described operation will be repeated.

Material starting over the plate or screen from a position between riffles 15 and 16 will be divided by the pyramid 11 of row 8, part of it tending to move to the right toward the riffle 16 and a part of it passing between the pyramid 11 and the riffle 16. Part of that which accumulates up between the said pyramid 11 and the riffle 16 will pass down the screen between the pyramid 11 and the riffle 16, but some of this material will be crowded over the riffle 16 into the space between the first two of the pyramids 11 of the second series or row 9 of pyramids 8.

In this way the material is given a more or less zigzag motion, being spread laterally or outwardly toward the side of the screen by the outwardly pointed inclined faces of the pyramids 11, 13, 14 and being concentrated toward the middle of the screen by the riffles 15 to 20 inclusive. As the riffles increase in height in a direction away from

the longitudinal axis 7—7 of the screen, the movement of the material toward the side of the screen is more and more impeded and the influence of the inclined riffles increasingly predominates so that, as a result of this, the material is prevented from unduly piling up along the sides of the screen and is kept in a comparatively even layer all over the screen.

10 As the large pieces of coal move over the apices of the pyramids they topple or turn over causing any small pieces of coal which are carried thereby to fall off. In this way during the traverse of the screen the small pieces of a size to pass through the openings or perforations 22 in the screen have an opportunity so to do, on account of the jogging action of the screen and the toppling of the large pieces over the apices of the pyramids, thus effecting a thorough screening of the coal to size.

In the modification shown in Figs. 4 to 6, the riffles 15 to 20 inclusive heretofore described, are dispensed with and the perforated plates 2 are provided with a series of rows of indented pyramids all of substantially the same height. The row 12' of pyramids 13, 14 arranged along the longitudinal axis of the screen comprises four-sided or quadrangular pyramids having the diagonal of their bases coincident with the longitudinal axis 7—7 of the plate. The other pyramids 11 and 11' are triangular. One base line of each of the triangular pyramids 11 and 11' is arranged parallel to the median line 7—7 of the plate. When a triangular pyramid is to impart to the coal passing thereover a movement toward the side of the screen, the other two sides of the base are directed outwardly toward the side of the plate or screen as instanced in the pyramids 11. When a triangular pyramid is to be used to concentrate the material passing over it toward the middle of the screen the two converging sides of the base point inwardly toward the median line 7 of the screen as instanced in the pyramids 11'. The straight side of the base of each triangular pyramid is preferably approximately in line with the middle of the adjacent base line of the next pyramid to the rear thereof.

In the form of my invention shown in Fig. 4, I have shown three staggered rows 8', 9', 10', respectively and one straight row 26 of indented triangular pyramids extending longitudinally of each half of the screen and symmetrically arranged on opposite sides of the row 12' of pyramids. Those pyramids 11 wherein the apices of the bases extend outwardly or away from the longitudinal axis 7—7 of the plate I term for convenience "spreading" pyramids, and those pyramids 11' the apices of the bases of which are directed inwardly toward the said axis I term "concentrating" pyramids. Thus, in stag-

gered row 8' I provide five spreading pyramids 11. In the second row 9' are three spreading pyramids 11 and two concentrating pyramids 11', one at each end of the said row. The third staggered row 10' duplicates the second staggered row in every particular. The fourth straight row comprises three pyramids 11' all of which are concentrating.

The course of the material over the screen is indicated by the arrows 27. As the material encounters the inclined face of a spreading pyramid 11 it is crowding outwardly away from the median line 7—7 of the screen and as the material encounters the concentrating pyramid 11' it will be moved inwardly toward the longitudinal axial line of the plate or screen.

In this way the material in traversing the screen will be kept evenly distributed over the screen and thoroughly agitated so that all the pieces of coal or similar material of a size to pass through the perforations in the screen will have an opportunity so to do during their travel of the length of the screen.

It will be noted that the pyramid projection imprinted into the screen shown in Fig. 4 are disposed over the screen symmetrically with respect to both longitudinal and transverse axes of the plate or screen and that the die for pressing these projections or indentations need be only substantially one-half the size of the plate, thus a die as wide as the plate and as long as three rows of indentations may be used to imprint the plate at two operations or a die as long as the plate and wide enough to imprint the central longitudinal row of pyramids and those between them and the sides of the plate may be employed.

Similarly, the plate shown in Fig. 1 may be imprinted into the perforated sheet in two operations with a die substantially as large as one-half of the sheet to be imprinted.

By so arranging the extensions symmetrically to one casting of the plate, the cost of making dies for pressing these screens is comparatively low and comparatively light, and light and inexpensive machinery may be employed for pressing the screens.

Having thus described my invention, what I claim and desire to protect by Letters Patent of the United States is:

1. A shaker screen comprising a perforated metal sheet or plate having rows of indented triangular pyramidal projections disposed over the upper surface thereof a base line of each pyramid being parallel to the axis of the screen.

2. A shaker screen comprising a perforated metal sheet or plate having a plurality of indented triangular pyramidal projections disposed over the upper surface thereof and arranged symmetrically with respect to an axis of said sheet or plate a base line of each pyramid being substantially

parallel to the longitudinal axis of the plate.

3. A shaker screen comprising a perforated metal sheet or plate having rows of indented triangular pyramidal projections disposed over the upper surface thereof and arranged symmetrically with respect to an axis of said sheet or plate, a base line of each pyramid being substantially parallel to the longitudinal axis of the plate.

10 4. A shaker screen comprising a perforated metal sheet or plate having parallel rows of indented triangular pyramidal projections disposed over the surface thereof and rising therefrom, said rows being arranged symmetrically with respect to the longitudinal axis of said plate, a base line of each pyramid being substantially parallel to the longitudinal axis of the plate.

20 5. A shaker screen comprising a perforated metal sheet or plate having a plurality of indented triangular pyramidal projections disposed over and rising from the surface thereof.

25 6. A shaker screen comprising a perforated metal sheet or plate having a plurality of triangular pyramidal projections arranged over the surface thereof, one base line of each of said projections being substantially parallel to the longitudinal axis of said plate.

30 7. A shaker screen comprising a perforated metal sheet or plate having a series of quadrangular pyramidal projections disposed along the longitudinal axis of said plate and acting to direct the material passing thereover outwardly toward the longitudinal sides of said plate, and rows of triangular pyramidal projections symmetrically disposed on opposite sides of the longitudinal axis of said plate and acting in the same manner.

35 8. A shaker screen comprising a perforated sheet or plate provided with rows of indented pyramidal projections acting to direct the material passing thereover outwardly toward the sides of said plate, with upwardly indented ripples between said rows of pyramidal projections acting to direct the material toward the longitudinal axis of said plate.

40 9. A shaker screen comprising a perforated plate, the surface thereof being provided with alternating parallel rows of spreading pyramidal projections and concentrating ripples.

45 10. A shaker screen comprising a perforated sheet or plate, having a series of quadrangular spreading pyramidal projections disposed with a diagonal of the bases thereof coincident with the longitudinal axis of said plate, and rows, symmetrically arranged on opposite sides of said axis, of triangular pyramidal spreader projections separated by concentrating ripples, said ripples being of increasing height as the series of ripples progresses toward the sides of the plate.

50 11. A shaker screen comprising a perforated sheet or plate and having its surface provided with inclined rows of pyramidal projections with a riffle between adjacent rows of projections, said ripples being of increasing height as the series of ripples approaches the sides of said plate and disposed parallel to the adjacent rows of ripples.

55 12. A shaker screen comprising a perforated metal sheet or plate having rows of indented triangular pyramidal projections disposed over the upper surface thereof and arranged symmetrically on opposite sides of the axis of said sheet or plate, the projections in one row being staggered with respect to the projections of the adjacent row, a base line of each pyramid being substantially parallel to the axis of said plate.

60 13. A shaker screen comprising a perforated metal sheet or plate having a series of pyramidal projections disposed along the longitudinal axis of said plate, and rows of pyramidal projections symmetrically disposed on opposite sides of said plate, said projections acting to direct the material passing thereover outwardly toward the sides of said plate, and means adjacent the sides of said plate to direct the material from the sides of said plate inwardly toward said projections.

65 14. A shaker screen comprising a perforated metal sheet or plate having a series of quadrangular pyramidal projections disposed along the longitudinal axis of said plate and acting to direct the material passing thereover outwardly toward the longitudinal sides of the plate and rows of triangular pyramidal projections symmetrically disposed on opposite sides of the longitudinal axis of the plate, a base line of said triangular pyramids being parallel to the axis of said plate.

70 15. A shaker screen comprising a perforated metal sheet or plate having a series of quadrangular pyramidal projections disposed along the longitudinal axis of said plate and acting to direct the material passing thereover outwardly toward the longitudinal sides of the plate and rows of triangular pyramidal projections symmetrically disposed on opposite sides of the longitudinal axis of the plate, a base line of said triangular pyramids being parallel to the axis of said plate.

75 In witness whereof, I have hereunto set my hand this 25th day of February, 1924.

HERBERT S. WOODWARD.
